CLAIM

The ornamental design for a therapy bar, as shown and described.

DESCRIPTION

FIG. 1 is a top front perspective view of a therapy bar.

FIG. 2 is a left-side view of a therapy bar.

FIG. 3 is a front view of a therapy bar; and,

FIG. 4 is a back view of a therapy bar.

Due the symmetric nature of the therapy bar, the right-side view, top view, and bottom view are the same as the left-side view, and therefore are not shown.

The broken lines in the drawings depict portions of the therapy bar that form no part of the claimed design.
